[57] CLAIM

The ornamental design for a plant pot liner, as shown and described.

DESCRIPTION

FIG. 1 is a perspective view of a plant pot liner showing my new design;

FIG. 2 is an enlarged front elevational view thereof;

FIG. 3 is an enlarged rear elevational view thereof;

FIG. 4 is an enlarged top plan view thereof;

FIG. 5 is a sectional view taken in the direction of the arrows on line 5—5 of FIG. 4;

FIG. 6 is an enlarged bottom plan view thereof; and,

FIG. 7 is an enlarged right side elevational view thereof, the left side being a mirror image.

FIG. 1

FIG. 2

FIG. 3

FIG. 4**FIG. 5**

FIG. 6

FIG. 7
